UNITED STATES PATENT OFFICE.

WILLIAM P. COLLINS, OF BOSTON, MASSACHUSETTS, ASSIGNOR TO AUTOMATIC AIR BRAKE COMPANY, OF BOSTON, MASSACHUSETTS, A CORPORATION OF MASSACHUSETTS.

BRAKE MECHANISM.

1,093,172.

Specification of Letters Patent. Patented Apr. 14, 1914.

Application filed February 25, 1913. Serial No. 750,518.

To all whom it may concern:

Be it known that I, WILLIAM P. COLLINS, a citizen of the United States, residing at Boston, in the county of Suffolk and State 5 of Massachusetts, have invented new and useful Improvements in Brake Mechanisms, of which the following is a specification.

This invention relates to new and useful improvements in brake mechanisms.

10 The object of the invention is to provide a powerful, compact and durable brake mechanism having a rotatable member which is adapted to be retarded or checked by controlling the passage of the fluid driven by 15 said rotating member, whereby friction and wear between the moving parts of said brake mechanism will be reduced to a minimum.

15 The object of the invention is further to provide a valve adapted to gradually check 20 the passage of said fluid.

The invention consists in the combination and arrangement of parts whereby the above objects and certain other objects hereinafter appearing are attained, as set forth in the 25 following specification and particularly pointed out in the claims.

Referring to the drawings: Figure 1 is a transverse section, partly in elevation, of a 30 brake embodying my invention. Fig. 2 is a sectional elevation of the device taken on line 2—2 of Fig. 1. Fig. 3 is a detail section, partly in elevation, taken on line 3—3 of Fig. 1 illustrating one means for opening and closing the ports.

35 Like numerals refer to like parts throughout the several views of the drawings.

In the drawings, 5 is a casing which is 40 preferably constructed in three parts comprising the cylindrical side wall 6 and the end walls 7 and 8, said three parts being preferably secured together by bolts 9. A piston blade carrier 10 is arranged within 45 the casing 5 and is secured to a shaft 11 having bearings 12 and 13 in the end walls 7 and 8 respectively. The carrier 10 is preferably provided with a cylindrical outer periphery 14.

A portion of the inner wall of the casing 5 is arranged concentric with the median 50 axial line of the shaft 11, while the inner wall of the remaining portion of said casing is substantially eccentrically arranged relatively to said median axial line and forms a chamber 15 having, adjacent opposite ends 55 thereof, ports 16 and 17.

The carrier 10 is provided with a series of radially disposed slots 18 within which pistons 19 are placed, said pistons preferably comprising a plurality of relatively movable blades 20 which during the relative movements between said casing and said rotary member are adapted to move radially within 60 said slots 18 and to engage the inner wall of the casing 5.

In operating the device either the casing 65 5 or the carrier 10 may be rotated relatively to the other, or both of said members may be rotated in opposite directions.

The preferred method of operating the device however is to rotate the carrier 10 for 70 the reason that in so doing the centrifugal force tends to retain said pistons, or the several blades comprising said pistons, in engagement at their outer ends with the inner 75 wall of said casing 5 or particularly that portion of the wall of the casing which lies concentric with the median axial line of said shaft 11.

As the carrier 10 is rotated in the direction of the arrow "a" Fig. 1 and the pistons 80 19 approach the chamber 15, for fear the centrifugal force will not always be sufficient to provide a proper contact between said pistons 19 and the wall of the casing 5 constituting said chamber, I have provided 85 means adapted to move said pistons radially relatively to the carrier 10 and to retain said pistons in contact with said wall, said means preferably including a cylindrical member 21 arranged to revolve about an axis substantially concentric with the eccentrically arranged wall of the casing 5 constituting the outer wall of the chamber 15.

The member 21 is constructed in the form 90 of a ring and is arranged within the carrier 95 10 to revolve upon rollers 22 journaled upon studs 23.

In the present invention the carrier 10 is provided with recesses 21', 21', at opposite ends thereof respectively and therefore to 100 evenly and uniformly sustain the pistons 19 in their proper relation to the wall constituting said chamber 15 two cylindrical members are provided, one within each of said recesses, said studs 23, which support the 105 rollers 22 constituting bearings for said rings, being mounted in the end walls 7 and 8 of said casing 5. The rings 21 preferably engage the inner periphery of the carrier 10 and as said carrier is rotated, said ring will 110

be revolved upon the rollers 22, there being two of said rollers to retain said ring concentric with said eccentrically arranged wall.

As the carrier is rotated, as hereinbefore described in the direction of the arrow "a", the pistons 19 as they approach and enter the chamber 15 will drive in advance thereof the air, liquid or whatever fluid it is found most desirable to employ therein, causing 10 said fluid to be ejected through the port 17, providing said port is open, while a partial vacuum will be formed at the rear of said piston causing air to enter said chamber through the port 16 providing said latter 15 port is open and consequently retarding the movement of said rotatable member but little or none.

When it is desired to check or slightly retard the movements of said carrier relatively to the casing 5, the ports 16 and 17 are slightly closed or completely closed as the case may be by means hereinafter described. When said ports are partially closed, the pistons 19 as they enter the chamber 15 and 20 pass the port 16 will, owing to the increasing cross sectional area of said chamber, gradually suck the air into said chamber through said port until they arrive at the point "b", which is the deepest portion of 25 said casing, the air then between the piston at said point and the next succeeding piston will be carried around with said rotary member until said piston and said succeeding piston arrive at positions upon opposite 30 sides of and equidistant from the point "b" then upon the continued movement of said pistons the air therebetween will be gradually compressed owing to the gradually decreasing cross sectional area of said chamber 35 40 15 and consequently the movement of said carrier will be retarded.

When it is desired to completely stop said carrier the ports 16 and 17 are completely closed preventing both the intake and the 45 discharge of the air to and from said chamber 15. In completely closing said ports however it is necessary that said closing be gradual in order to prevent an excessive shock to the moving parts of the device. To 50 accomplish this, valves are provided for said ports each of which include a rotary screw-threaded member 24, the screw-threads thereof being of exceedingly sharp pitch and engage corresponding threads formed preferably upon the exterior of a stem 25. This 55 stem is further provided with a series of passages 26 which extend radially through said stem opening into a passage 27 which com-

municates with the chamber 15, and are helically arranged thereabout consequently as 60 said member 24 is rotated relatively to said stem and moved in the direction of the arrow "c" Fig. 3, said passages will be gradually covered and closed. The member 24 is also provided with a conical shaped projection 28 65 constituting a needle valve, which extends inwardly into the passage 27. The member 24 is further provided with openings 29 arranged about the projection 28 and as said member is moved longitudinally of the stem 70 25 said projection will open and close the end of the passage 28 and thus prevent the escapement or admission of more or less air or liquid through said passage.

A rotary motion is imparted to the member 24 by a lever 30 which in turn is preferably actuated by a lever 31 connected to said lever 30 by a link 32, said link extending from the operating lever 30 of one of said valves to the operating lever 30 of the other 80 85 of said valves thus causing said valves to be simultaneously opened or closed.

Having thus described my invention what I claim and desire by Letters Patent to secure is:

A device of the class described having, in combination, a cylindrical piston blade carrier, a casing within which said carrier is arranged, said casing having a chamber formed outside of and adjacent to the periphery of said carrier, the inner wall of said casing within said chamber being eccentrically arranged relatively to the axis of said carrier, said chamber having ports adjacent opposite ends thereof, piston blades on 95 said carrier adapted to engage the inner wall of said casing, means to create a relative rotary movement between said carrier and said casing, means to cause said blades to engage the inner wall constituting said 100 chamber during said rotary movement, said means including rings mounted to revolve about an axis substantially coincident with the axis of said eccentrically arranged wall, said rings adapted to be engaged by said 105 pistons only when said pistons are passing through said chamber, rollers adapted to support said rings, and means to open and close said ports.

In testimony whereof I have hereunto set 110 my hand in presence of two subscribing witnesses.

WILLIAM P. COLLINS.
